Fig. 4

Fig. 5

Fig. 6

FIG. 1 is a side elevational view of the outside rear view mirror for vehicles of the invention;

FIG. 2 is a front elevational view of FIG. 1;

FIG. 3 is a rear elevational view of FIG. 1;

FIG. 4 is a bottom plan view of FIG. 1;

FIG. 5 is a fragmentary side elevational view of a modified form thereof, it being understood that the remainder of the design is the same as shown in FIGS. 1 through 4; and

FIG. 6 is a front elevational view of the modification shown in FIG. 5.

The side opposite to the side elevational views shown in FIGS. 1 and 5 are respectively identical and therefore not in need of being shown.

I claim:

The ornamental design for an outside rear view mirror for vehicles, as shown and described.
